CIRCUIT INTERRUPTER

Charles L. Craddock, North Hollywood, Calif.

Application September 30, 1957, Serial No. 687,140

5 Claims. (Cl. 200—87)

This invention relates generally to interrupters and more particularly to a magnetically operated electric circuit interrupter of the type frequently used in the operation of flashing warning signals or lights.

In recent years the use of warning signal lights of the flashing type has become quite widespread in highway and similar construction work. In general, these signal lights are self-contained, and include a battery, a circuit interrupter of some type, a transformer, and a high voltage gaseous discharge tube. Frequently, the circuit interrupter is combined with the transformer and includes a pair of contacts, one of which is urged toward a gap in the transformer core when the primary circuit to the transformer is completed. Movement of this contact moves the second contact, mounted upon a pivoted arm or wheel, so that the impulse imparted to the wheel or arm carries the second contact away from the first contact, breaking the circuit to the transformer primary, and releasing the first contact. A spring then returns the second contact to the first contact, thereby completing the electrical circuit to the primary of the transformer, whereupon the cycle is repeated. Each time the contacts separate, a high voltage is induced in the secondary winding of the transformer, and the gaseous conduction lamp, connected to the secondary of the transformer, is thus briefly illuminated.

While this form of construction is relatively simple, the use of the pivotally-mounted arm or wheel, the bearings therefor, and the return spring all add complications that result in a somewhat expensive piece of equipment that has a number of points that can cause trouble.

To reduce the drain upon the batteries, it is desirable to have the circuit interrupter make and break the circuit with a frequency in the general range of from one-half to two cycles per second. Occasionally even a slower speed is desired, and the device may be operated once every three or four seconds. With such frequency, the mass of the pivoted arm or wheel becomes greater, and the contacts sometimes fail to separate quickly, causing burning and pitting of the contacts, with consequent faulty operation.

It is therefore a major object of the present invention to provide an electrical circuit interrupter that overcomes many of the disadvantages and objections of the prior devices.

Another object of the invention is to provide such a circuit interrupter that is very simple in its construction and has very few wearing parts that may cause trouble and malfunctioning of the apparatus.

It is a further object of the invention to provide such a device in which the contacts are open and closed quickly so that burning and pitting of the contacts is greatly reduced.

Still another object of the invention is to provide a circuit interrupter of this type that is less expensive to construct and requires less skilled labor in its assembly.

These and other objects and advantages of the inven-

tion will become apparent from the following description of a preferred form thereof, and from the drawings illustrating that form in which:

Figure 1 is a side elevational view of a circuit interrupter constructed in accordance with this invention, with the associated electrical circuitry being indicated;

Figure 2 is a plan view of the interrupter shown in Figure 1; and

Figure 3 is a schematic electrical circuit of the entire system.

Referring now to the drawings and particularly to Figure 1 thereof, the numeral 10 indicates generally the transformer and circuit interrupter, the primary of the transformer being connected to a battery 11, and the secondary of the transformer being connected to a suitable lamp 12. In this respect, the electrical circuit of the circuit interrupter is similar to those of previous devices. However, the mechanical construction of the circuit interrupter, and particularly the timing mechanism thereof, is considerably different. Thus, where previous devices have used spring-biased oscillating arms or wheels, the present device makes use of a generally cup-shaped disk, here referred to as a suction cup, that is driven against a surface, and then allowed to separate from the surface. Thus, in Figure 1, a rubber suction cup 13 is adapted to be driven against a plate 14, driving out some of the air originally trapped between the cup and the plate, and causing the cup to adhere to the plate. Air then gradually leaks between the cup 13 and the plate 14, and after a period of time, a sufficient amount of air has entered into the space within the cup to permit the latter to separate from the plate. By a proper control of the characteristics of the cup 13 and plate 14, the time required for this separation can be adjusted to the desired value.

One method of using such a timing mechanism is illustrated in Figure 1. In this figure, the numeral 15 indicates the customary core of an interrupter and transformer assembly, the core having a magnetic gap 16 that interrupts the otherwise complete low-reluctance magnetic path provided by the core. Upon the core 15 is placed transformer winding 17 having a primary winding 20 with leads 21 and 22. A secondary winding 23 has leads 24 and 25 therefrom, and it will be appreciated that the transformer winding 17 may be a so-called autotransformer, in which the secondary winding is a continuation of the primary winding, or may be of the type in which two separate windings are used.

Attached to the core 15 is an insulating block 26 on which are mounted a pair of leaf members 27 and 28. The leaf members 27 and 28 project from the block 26, and at its free end, the upper leaf member 27 carries a contact point 30. The lower leaf member 28 extends a greater distance from the block 26, and carries a contact member 31, aligned with the contact point 30 of the upper member. Continuing on from that contact point 31, the lower leaf member 28 carries an armature plate 32 adapted to bridge the magnetic gap 16, and at its outer end, carries the suction cup 13. The upper leaf member 27 is preferably rather stiff, while the lower leaf member 28 is relatively flexible and may be described as a reed.

In its normal position, with the transformer winding 17 deenergized, the lower reed 28 assumes the position indicated in solid outline in Figure 1, with the contact points 30 and 31 touching each other and completing an electrical circuit. The armature plate 32 is spaced from the core 15 and the magnetic gap 16 therein, while the suction cup 13 is spaced from the plate 14, all as indicated.

The plate 14 preferably takes the form of an angle 33 having one leg, forming the plate 14, extending generally perpendicular from the adjacent edge of the core

15, and substantially parallel to the lower surface of the suction cup 13. The other leg of the angle 33 is attached to the core 15 by any suitable means, such as the screw 34.

In order to secure desirable and consistent results, it is important that the plate 14 be formed of a material that is non-injurious to the suction cup 13 and which has a smooth surface against which the edges of the suction cup may seal. Most metals have a tendency to react with the material of the suction cup 13, and hence are undesirable. While many different materials will be found suitable, it has been found that hard, smooth-surfaced types of plastics, such as are available under the trade names "Synthane," and "Teflon," and also nylon, are very satisfactory. These materials may be extruded, and are available in angle sections, such as section 33. The extruded section may then be cut into short lengths, and one such length applied to the core 15 in the manner shown.

The electrical circuit is completed by connecting the lead 21 from the primary of the transformer 17 to one of the leaf members, such as the reed 28, and the leaf member 27 is then connected, preferably through a switch 35, to the battery 11. The other terminal of this battery is connected to the remaining terminal 22 of the primary winding. A capacitor 36 is connected between the leaf members 27 and 28 so that arcing between the contact points 30 and 31 is reduced.

With the various parts initially in the position indicated in solid outline in Figure 1, when the switch 35 is closed, a circuit is completed from the battery 11, through the contacts 30 and 31, and to the primary of the transformer 17. The energization of the primary produces a magnetic field within the core 15, but in the vicinity of the magnetic gap 16, this magnetic field spreads outwardly and passes through the armature plate 32, pulling the plate and the reed 28 toward the core 15. This movement of the reed 28 toward the core 15 drives the suction cup 13 into contact with the plate 14, and separates the contacts 30 and 31 so that the circuit to the primary of the transformer 17 is broken. With the breaking or interruption of the primary circuit, the magnetic field collapses causing the induction of a high voltage in the secondary winding that is applied to the gaseous lamp 12. The lamp thus flashes brightly, and then becomes dark.

After the suction cup 13 has been driven against the plate 14, air or other ambient gas leaks into the space between the cup and the plate, and the resilience of the reed 28 and the resilience of the material forming the suction cup 13 eventually cause the cup to separate from the plate, whereupon the reed 28 returns to its original position, thereby again completing a circuit to the primary of the transformer winding 17. The cycle then repeats, and continues to do so as long as power is supplied to the circuit including the primary winding 20 and the contacts 30 and 31. For convenience, the electrical circuit is shown in schematic form in Figure 3.

It will be apparent that the length of a cycle can be varied over a wide range by a suitable choice of materials and various other parameters. Thus, the stiffness or hardness of the suction cup 13 is a very important factor, since this determines how far the center of the cup is driven toward the plate 14, and consequently how much air is forced from between the cup and the plate. Likewise, the size of the cup 13, the force with which it is driven against the plate, and the stiffness of the reed 28 are all factors that will control the speed of circuit interruption. In each case, however, it will be appreciated that the size of the plate 14 should be sufficient to completely cover the adjacent surface of the suction cup 13 when the latter is driven against the plate, since otherwise the suction action is completely eliminated.

In order to minimize the possibilities of dirt, oxida-

tion, and other undesirable effects from interfering with the operation of the circuit interrupter, it is preferable to place the interrupter and transformer assembly 10 in a container that is preferably filled with an inert gas and then sealed. In this way, the interrupter will maintain its original calibration for an extended period of time, and the problem of high voltage flash-over is greatly reduced. This latter is particularly important if the device is used at high altitudes.

By way of a specific example, and not as a limitation, a circuit interrupter has been constructed making use of a suction cup 13 having an external diameter of approximately three-quarters of an inch. The cup is made of soft gum rubber, and is normally spaced, when the switch 35 is open, a distance of approximately three-sixteenths of an inch from the adjacent surface of the plate 14. The depth of the cup, i.e., the depth of the recess adjacent the plate 14, is approximately one-fourth inch, and when the armature plate 32 is attracted to the core 15, the total travel of the base of the cup 13 is approximately one-fourth inch. The first three-sixteenths of an inch travel of the cup are thus spent in moving the cup into contact with the plate 14, and the last one-sixteenth inch is spent in pressing the lips of the cup against the plate. With such a device, the frequency of operation of the circuit interrupter is approximately seventy cycles per minute. When the interrupter is enclosed within a pressurized container, the inert gas in the container is preferably nitrogen or helium, and is maintained at a pressure of approximately one and one-half atmospheres.

From the foregoing, it will be seen that there has been provided a device fully capable of achieving the objects and securing the advantages heretofore set forth. It will be apparent to those skilled in the art that modifications may be made therein that do not depart from the broad concept of the invention, and consequently the patent is not to be restricted to the particular form or arrangement of parts herein described and shown, except as limited by the following claims.

I claim:

1. An interrupter of the class described which includes: movable means normally urged to a first position; a pair of electrical contacts, one of said contacts being moved with said movable means and said contacts being closed when said movable means are in said first position; means actuated by the closure of said contacts for moving said movable means from said first position to a second position, where said contacts are open; whereby said movable means repetitively moves between said first and second positions; suction cup means connected to said movable means for movement therewith; and a member having a smooth surface adjacent said suction cup means and adapted to be engaged thereby when said movable means is moved to said second position, said suction cup means being held to said member for a predetermined period of time by reason of the reduced pressure within said cup means, and thereafter releasing from said member and releasing said movable means for return to said first position.

2. An interrupter of the class described which includes: support means; movable means mounted on said support means and resiliently urged toward a first position; a pair of electrical contacts, one of said contacts being held substantially immovable with respect to said support means, and the other of said contacts being moved with said movable means, said contacts being closed when said movable means is in said first position; means actuated by the closure of said contacts for driving said movable means from said first position toward a second position, where said contacts are open, said driving means being active only while said contacts are closed, whereby said movable means repetitively cycles between said first and second positions; suction cup means connected to said movable means for movement therewith; and a member mounted on said support means

and having a smooth surface adjacent said suction cup means, adapted to be engaged thereby when said movable means is moved to said second position, said suction cup means being held to said member for a predetermined period of time by reason of the reduced pressure within said cup means, and thereafter releasing from said member and releasing said movable means for return to said first position, whereupon said contacts are again closed and the cycle is repeated.

3. An interrupter of the class described which includes: a magnetic frame having a magnetic gap therein; means mounted for movement with respect to said magnetic frame and resiliently urged toward a first position with respect thereto; a pair of electrical contacts, one of said contacts being held substantially immovable with respect to said magnetic frame and the other of said contacts being moved with said movable means, said said contacts being closed when said movable means is in said first position; magnetizable means mounted on reed means for movement therewith and aligned to bridge said magnetic gap, said magnetizable means being spaced from said magnetic frame when said movable means is in said first position; coil means on said magnetic frame, adapted to be energized by the closure of said contacts to produce a magnetic field in said magnetic frame, thereby attracting said magnetizable means and moving said movable means from said first position to a second position, where said contacts are open; suction cup means connected to said movable means for movement therewith; and a member substantially immovable with respect to said magnetic frame and having a smooth surface adjacent said suction cup means and substantially parallel to the lip thereof, adapted to be engaged thereby when said movable means is moved to said second position; said suction cup means being held to said member for a predetermined period of time by reason of the reduced pressure within said cup means, and thereafter releasing from said member and releasing said movable means for return to said first position, whereupon said contacts are again closed and the cycle is repeated.

4. An interrupter of the class described which includes: a magnetic frame having a magnetic gap therein; reed means supported at one end and held therat against movement with respect to said magnetic frame, the other end of said reed means being movable toward and away from said frame but resiliently biased away from said frame toward a first position; contact support means substantially immovable with respect to said magnetic frame; an aligned pair of electrical contacts, one of said contacts being mounted on said contact support and the other being mounted on said reed means for movement therewith, said contacts being closed when said reed means is in said first position; magnetizable means mounted on reed means for movement therewith and aligned to bridge said magnetic gap, said magnetizable means being spaced from said magnetic frame when said reed means is in said first position; coil means on said magnetic frame, adapted to be energized by the closure of said contacts to produce a magnetic field in said magnetic frame, thereby attracting said magnetizable means and moving said reed means from said first position to a second position, where said contacts are open;

suction cup means mounted on the movable end of said reed means for movement therewith; and a member substantially immovable with respect to said magnetic frame and having a smooth surface adjacent said suction cup means and substantially parallel to the lip thereof, adapted to be engaged thereby when said reed means is moved to said second position, said suction cup means being held to said member for a predetermined period of time by reason of the reduced pressure within said cup means, and thereafter releasing from said member and releasing said reed means for return to said first position, whereupon said contacts are again closed and the cycle is repeated.

5. A circuit interrupter of the class described which includes: a magnetic frame having a magnetic gap therein; an electromagnetic coil mounted on said frame; reed-mounted magnetic armature means, said armature means being adapted to bridge said magnetic gap but normally being spaced therefrom, one end of said reed mounting being anchored to said frame at a point remote from said gap, and the other end of said reed being movable with said armature and projecting beyond said frame; a first electrical contact mounted on said reed mounting and movable therewith; a second electrical contact mounted by said frame and substantially immovable with respect thereto, said first and second contacts being so positioned and arranged that said contacts are in closed circuit relationship with each other when said armature is in said normal or first position, and are in open circuit relationship when said armature is in a second position adjacent said gap, said first and second electrical contacts being in series with said coil; suction cup means mounted on said other or movable end of said reed mounting and movable therewith, said suction cup means being mounted on said reed mounting for movement thereby in a direction parallel to the axis of symmetry of said suction cup means; and cooperating means mounted on said frame and having a surface parallel to the lip of said suction cup means, said surface being spaced from said lip when said armature is in said first position; and being engaged by said lip when said armature is in said second position, said cooperating means being mounted for adjustment with respect to said frame, and so positioned that movement of said armature from said first to said second position drives said suction cup means against said cooperating means and distorts said suction cup means to produce a reduced pressure therein, thereby temporarily holding said suction cup to said cooperating means and restraining return movement of said armature to said first position.
